UNITED STATES PATENT OFFICE.

JOHN DAVIDSON, OF MANCHESTER, ENGLAND.

INTERNAL-COMBUSTION ENGINE.

1,317,356.

Specification of Letters Patent. Patented Sept. 30, 1919.

Application filed July 7, 1919. Serial No. 309,146.

To all whom it may concern:

Be it known that I, JOHN DAVIDSON, a subject of the King of Great Britain, residing at Manchester, in the county of Lancaster, England, have invented certain useful Improvements in and Connected with Internal-Combustion Engines, of which the following is a specification.

This invention relates to improvements 10 in and connected with the two cycle type of internal combustion engine described in my British application for Letters Patent No. 119,401.

The present invention has for its object 15 to provide further embodiments of the said type of engines and thereby increase the efficiency and reduce the weight thereof.

The object of the invention is chiefly to render the pumps of said type of engines, 20 double acting.

I attain these objects by the means illustrated in the accompanying two sheets of drawings in which, Figures 1 and 3 are vertical sections and Figs. 2 and 4 respectively 25 end views of two cylinder engines constructed in accordance with this invention.

Referring to the said figures generally, 30 *a, a* are the working cylinders, *c, c* the charging cylinders and *e, e* the working pistons, *f, f* are the tubular extensions on the working pistons having ports *g, h* and forming a passage *i* between the charging cylinders *c, c* and working cylinders *a, a* to serve as mixture distributing valves.

35 *h h* are the double acting pistons of the charging pumps formed in accordance with this invention on the said tubular extensions.

In the embodiment shown in Figs. 1 and 2, the cranks are arranged opposite each 40 other and consequently the top side of one charging cylinder or pump and the bottom side of the other, are used together, by forming admission ports *m* at the top side of the left hand charging cylinder or pump and coupling said ports together by a pipe 45 *n*. By a similar set of ports and a pipe employed in front of the engine, Fig. 2, the bottom side of the right hand charging cylinder or pump is coupled to the top side of the 50 left hand charging cylinder or pump.

One of the charging cylinders is controlled at its top end and the other at its bottom end, by the tubular extension *f*, that is to say, when the charging piston of 55 one cylinder is in the top position, that of the other is in the bottom position, so that

when the tubular extension *f* is in the top position, the charge can enter through ports *g, h* therein.

The discharge from the charging cylinder *c*, is also controlled by the tubular extension *f*, which on the down stroke cuts off communication with the passage *x* and the charging cylinders *c*, and working cylinders *a* do not come into communication with the charging 60 cylinders until port *g* in the tubular extension is opposite the port *l* in the working cylinders.

By the arrangement described both sides 65 of the charging pistons are used, the size of the charging pumps is considerably reduced and uselessly pumping air on the one side is avoided.

The pumps of the engine described operate as follows:—

As the pistons commence to move, a partial vacuum is created at the bottom side 70 of the right hand and the top side of the left hand charging cylinders or pumps, also in the ports *m, m'* and the pipe *n*. This suction is continued until the right hand piston is in a similar position to that shown for the left hand charging cylinder or pump, and the ports *g* in piston tubular extension *f* over run the inlet passage *x* which is 75 coupled to the inlet mixture pipe when a charge is immediately drawn in and fills the bottom side of the right hand and top side of left hand charging cylinders or pumps and connecting pipe *n*.

80 On the return stroke of the pistons, the piston tubular extension *f* first closes the inlet passage *x* and the charge is then compressed until the pistons again arrive in the position shown in Fig. 1, when the charge 85 immediately expands into the right hand working cylinder through the tubular extension of piston *e* and out at *g*.

90 The same order of events takes place on the top side of the right hand and the bottom side of the left hand charging cylinders or pumps in charging the left hand working cylinder.

95 It will be readily understood that in the engine described said piston tubular extension takes the place of the distributing valve 100 for the charging cylinders or pumps.

105 Referring to the engine shown in Figs. 3 and 4 such has also working cylinders *a, a* and charging cylinders *c, c* arranged tandem fashion, tubular extension *f, f* and the working pistons *e, e* with double acting 110

charging pistons *k*, *k* as described with reference to Figs. 1 and 2. In this embodiment however, a piston valve *o* is arranged between the charging cylinders *c*, *c* actuated from the crank shaft of the engine and adjusted to control the inlet *p* to the charging cylinders *c*, *c*, the top of one charging cylinder or pump being connected like in Figs. 1 and 2, with the bottom of the other.

The top and bottom sides of said piston valve at *R*, *R*, are coupled to the inlet mixture pipe and ports *S*, *S* are in connection with the top of the left hand and the bottom of the right hand pump, and the bottom of the left hand and the top of the right hand pump.

As the right hand charging cylinder or pump piston rises from the position shown and the left hand one descends, said piston valve is moved downward by its eccentric and uncovers port *S* allowing a charge of mixture to be drawn into the under side of the right hand and top side of the left hand charging cylinder or pump. When the pistons reach the end of their stroke, said piston valve will again rise and cut off ports *S*. The charge is then compressed on the return stroke and delivered through the piston tubular extension *f* and ports *g*, *g'* to the right hand working cylinder.

The left hand working cylinder is charged in a similar manner as the right hand one described.

I claim:

1. In a two-stroke cycle two cylinder internal combustion engine, a pair of working cylinders each having an exhaust port at a point intermediate its ends, and a charging cylinder extending from one end,

one of said charging cylinders having an inlet port near its outer end and the other having an inlet port near its inner end; working pistons in said working cylinders and arranged for simultaneous movement in reverse directions, and charging pistons connected to said working pistons and arranged for operation in said charging cylinders, each charging piston having a tubular portion and providing a passage for working fluid and also having ports near its inner end and at a point intermediate its ends.

2. In a two-stroke cycle two cylinder internal combustion engine, a pair of working cylinders each having an exhaust port at a point intermediate its ends, and a charging cylinder extending from one end, one of said charging cylinders having an inlet port near its outer end and the other having an inlet port near its inner end; working pistons in said working cylinders and arranged for simultaneous movement in reverse directions, and charging pistons connected to said working pistons and arranged for operation in said charging cylinders, each charging piston having a tubular portion and providing a passage for working fluid and also having ports near its inner end and at a point intermediate its ends, and a working fluid inlet pipe each end of which communicates with one end of said charging cylinders, and a piston valve in operative connection with said inlet pipe to control the inlet of the working fluid.

Signed at Manchester, in the county of Lancaster, this 25th day of June, 1919.

JOHN DAVIDSON.
